UNITED STATES PATENT OFFICE.

FELIX WESTWOOD, OF WHEELING, WEST VIRGINIA.

MACHINE FOR DOUBLING METAL PLATES.

SPECIFICATION forming part of Letters Patent No. 611,539, dated September 27, 1898.

Application filed March 29, 1898. Serial No. 675,622. (No model.)

To all whom it may concern:

Be it known that I, FELIX WESTWOOD, a citizen of the United States, residing at Wheeling, in the county of Ohio and State of West Virginia, have invented new and useful Improvements in Machines for Doubling Metal Plates, of which the following is a specification.

My invention relates to an improved machine for doubling metal plates, and has for its object to provide a machine for this purpose which shall operate in a simple, positive, and accurate manner to fold or double the metal plates and subsequently deliver the folded plate at a point convenient to the operator.

Further objects of the invention relate to details of construction and operation of parts of the machine, all of which will be more readily understood from the following description, in connection with the accompanying drawings, in which—

Figure 1 is an end elevation of a plate-doubling machine constructed in accordance with my invention. Fig. 2 is an elevation looking at the rear of the machine. Fig. 3 is a detail vertical sectional view. Fig. 4 is a detail plan view of the parts shown in Fig. 3. Figs. 5 and 6 are detail views hereinafter explained.

The numeral 1 indicates the main supporting-table, upon which the plates to be doubled are placed. This table comprises side members 2 3 and end members 4 5, secured together in the ordinary or any preferred manner. This table is supported on legs 6, which are suitably flanged or otherwise formed at the bottom to permit the table to be firmly secured to the mill-floor.

The numeral 7 indicates an upright which supports the greater portion of the machinery for operating the creasing-knife and other parts of the device, as hereinafter described. This upright therefore is of great strength and is firmly bolted to the mill-floor. Journaled in this upright near its upper end is a shaft 8, which projects outward on either side of said upright. On the end of shaft 8 projecting at the front of the machine is secured a pulley 9, driven by a belt 10. The pulley 9 is the main driving-pulley of the machine.

In lieu of the construction just described I may employ a separate belt-pulley for the belt 10 and provide suitable clutch mechanism between this pulley and the driving-pulley 9; but as such features of construction are within the knowledge of all skilled mechanics I have not deemed it necessary to further illustrate this portion of the machine. 60

Secured on the pulley 9 is a bearing-block 11, which is provided with a dovetailed guide-groove 12, in which is slidably secured a cross-head 13. Said cross-head does not reciprocate in said guide-groove in the operation of the machine, but is only designed to be adjustable therein, being secured in its adjusted position by means of a screw-bolt 14 or similar device. Said cross-head 13 carries a crank-pin 15. 70

The numeral 16 indicates a connecting-rod having at its upper end a longitudinal slot 17, in which is located the crank-pin 15. The purpose of having a slotted connection between the connecting-rod 16 and the crank-pin 15 will presently appear. 75

The numeral 18 indicates a shaft one end of which is journaled in the lower portion of the upright 7 and has secured near its end a pinion 19, which works in a slot 20 formed in the lower part of the upright 7. Secured on the face of the upright 7 are two guide-blocks 21 22, which near their outer edges are correspondingly grooved, as indicated at 23 24, to form a guide or working way for the flanged edges of a rack-bar 25, the teeth on which project between the inner sides of the guide-blocks 21 22 and engage the teeth of the pinion 19. At its upper end said rack-bar is pivotally connected, as indicated at 26, to the lower end of the connecting-rod 16. 80

On the opposite squared end of the shaft 8, at the rear of the machine, is secured a small drive-wheel 27, having a crank-pin 28, on which is pivotally secured the upper end 95 of a connecting-rod 29, the lower end of which is adjustably secured, as by a screw-bolt 30, in a longitudinally-disposed slot 31 of a lever-arm 32, which is fulcrumed intermediate its ends, as at 33, on the upright 7. Said lever-arm has a rearward extension 34 for a purpose to be presently described. At its opposite end said lever-arm is provided with a longitudinally-disposed slot 35. 100

The reference - numeral 36 indicates the creasing-blade, the body of which is preferably formed of iron, the lower portion affording a knife-edge, being preferably made 5 of steel. Secured on the creasing-blade centrally of its width and at a suitable height thereon is a stud 37, having journaled thereon a roller 38, which is designed to work in the slot 35 of lever-arm 32. A suitable nut and 10 washer 39 confines the slotted end of said lever-arm on the stud 37.

The numerals 40 41 indicate two parallel uprights, which are provided on their inner opposite sides with grooves 42, affording 15 guideways for the creasing-blade 36. Said uprights 40 41 are firmly secured in cross-beams 43, which in turn are firmly secured at their end portions to the upright 7. One of said uprights, 41, is extended down through 20 and secured in the side frame 2 of the table 1. The opposite upright 40 is cut away, as shown at 44, to permit the sheets to be folded to be placed on the table. The inner side of 25 the frame 3 of the table is provided with a groove for the creasing-blade, which forms a continuation of the groove in the upright 40.

The shaft 18 extends through and is journaled in the frame-pieces 2 and 3 of the table 1. The numeral 45 indicates a tilting platform, which is secured at its upper end on shaft 18, by which its free end is moved upward and downward in the operation of the machine, to be presently described. Said platform comprises the side members 46 47, connected and braced by the cross-stays 48. Extending between and journaled in the side members 46 47 are rollers 49, forming the upper bearing-surface of said platform and upon which the doubled plate is designed to 35 rest, as will presently appear. At its free end said platform is provided with a projecting plate 50, which extends entirely across said platform and is inclined upward toward the upper end thereof.

45 The numerals 51 52 indicate the doubling-rollers, which are located centrally of the length of table 1 and are respectively journaled at their ends in slide-blocks 53, which work in grooves 54, formed by securing supplemental frame-pieces 55 on the inner sides of the side bars 2 3. At the opposite end to that in which the rollers 51 52 are journaled the slide-blocks 53 are respectively engaged by one end of a coiled spring 56, which springs 50

55 are located in the grooves 54 and at their opposite ends bear against a stationary portion of the framing of the table. The coiled springs 56 tend normally to press the slide-blocks 53, carrying the rollers 51 52, toward each other. 60 Journaled in the frame-pieces 55 on either side of the doubling-rollers 51 52, respectively, are two surface-rollers 57, which, with said rollers 51 52, serve to support the metal plate to be doubled upon the table. Suitable 65 set-screws 58 may pass through the end of the table and bear against the ends of the springs

56 for the purpose of regulating the tension of the doubling-rollers 51 52.

The numerals 59 60 indicate, respectively, two gage-plates which are located at the ends 70 of the table. Said gage-plates are provided at their ends with right-angled depending portions 61, provided on their inner faces with guide-grooves 62, which work over ribs 63 on the outer sides of the side members 2 3. 75 At each opposite end thereof these gage-plates have a motion toward and from the doubling-rollers and are operated by the following mechanism:

The numeral 64 indicates a trip-lever, which 80 intermediate its ends is provided with a slot 65, in which slot passes a binding-screw 66, which engages in the rear face of the upright 7, by which means said trip-lever is adjustably pivoted on said upright. At its inner 85 end said trip-lever is provided with a slot 67.

The numeral 68 indicates a shaft which is journaled in the side members 2 3 of the table, extending entirely across the table and projecting from either side thereof. At the 90 side of the table adjacent to the upright 7 the shaft 68 projects a considerable distance from the side member 2 and on said projecting end is provided with a crank-arm 69. A link 70 connects the free end of said crank-arm 69 and the slotted end of the trip-lever 64. Secured on the shaft 68 at either side of the machine and adjacent to its side members are what I will term two "crank-plates" 71, which have a vertical projection above and below the shaft 68. Pivoted secured at one end to each projecting portion 61 of the gage-plates 59 and 60 is a connecting-rod 72, which near their outer ends are provided with longitudinally-disposed slots 73.

105 It will be understood that there are two connecting-rods 72 at each side of the machine, and the connecting-rods of each pair extend inward, respectively, above and below the shaft 68 and are adjustably secured to the 110 projecting portions of the crank-plates 71 by set-screws 74, passing in said slots and engaging in said crank-plates. On the projecting inner end of each lower connecting-rod 71 is secured one end of a coiled spring 75, which 115 at its opposite end is connected to the frame of the machine. Secured on the outer projecting end of the trip-lever 64 is a block 76, which is designed to contact with the free end of the trip-lever 64.

120 Secured on the upper portion of the side member 2 are two adjustable stops 77, against which the inner edges of the plates bear when placed upon the table. Secured on the upper side of each gage-plate 59 is a diverging 125 guide 78, at the inner end of which is located a friction-roller 79, which tends to overcome friction of the guides in placing the plates upon the table. On the side member 3 are secured two downwardly-curved guide-fingers 80, which assist the operator in placing the plates upon the table and prevent the 130

plates from striking the front of the table. Guide-fingers 80^a may also be placed on the front ends of the gage-plates 59, as shown. Slidably supported upon the upright 40 is a 5 guide-finger 81, which is curved reversely to the guide-fingers 80. The guide-finger 81 operates to prevent the metal plates from striking the upright 40 or the creasing-blade 36 and assists, in conjunction with the fingers 80, 10 in guiding the plates when placing them on the table. Said finger 81 differs from the fingers 80, however, in having a vertical movement.

It is the purpose of the gage-plates 59 to 15 insure that the metal plates shall be doubled in the center in the operation of the machine.

The numeral 82 indicates a receiving-table for the doubled sheets, which is removably 20 secured in an inclined position in slots 83 formed in the legs of the table, its inner end projecting inward when in position to a point near the end of the tilting platform 45, secured on the shaft 18. The outer end of said 25 table has a stop 85.

The operation of the machine is as follows: The parts being in the position shown in Fig. 1, a metal plate to be doubled is placed upon the table 1, its opposite ends resting upon 30 the gage-plates 59 and bearing against or in close proximity to the friction-rollers 79. The pulley 9 being revolved the connecting-rod 16 raises the rack-bar 25, which operates through the pinion 19 to revolve the shaft 18 and lower the tilting platform 45. At the 35 same time the small drive-wheel 27 is revolved, which operates through the medium of connecting-rod 29 and lever-arm 32 to lower the creasing-blade 36, said creasing-blade and 40 tilting platform moving downward simultaneously. In the position in which the parts are shown in Fig. 1 the block 76 on lever-arm 32 is in contact with the free outer end of trip-lever 64, in which position the gage-plates 45 59 are held in their extreme outer position on the table against the resistance of the coiled springs 75. As the outer extended end 34 of the lever-arm rises in the movement above described the block 76 is lifted from the trip-lever 64, and the springs 75, drawing on the 50 connecting-rods 72, operate to move the gage-plates inward, the crank-plates 71 being thereby rocked, and through the medium of the crank-arm on shaft 68 and the link 70, connecting said crank-arm with the trip-lever 64, said trip-lever will have its inner end depressed and its outer end elevated. In order to assist this movement of the trip-lever, I 55 may suspend or otherwise secure on its inner end, adjacent to the point of connection with the link 70, a weight 84. As the creasing-blade 36 descends it contacts with the upper surface of the metal plate (indicated by 86) and starts to press the same downward between the spring-pressed rollers 51 52. At 60 the same time the gage-plates 59 move inward, and should the metal plate being dou-

bled not reach exactly between the rollers 79—that is, be shorter than the distance between said rollers—the latter in moving inward will contact with one or the other edge of the metal plate and center the same upon the table. Furthermore, the rollers 79, pressing uniformly at both ends upon the metal plate, will assist the doubling operation by insuring that both ends of the metal plate shall move inward at the same time in the initial creasing of the plate, thereby tending to prevent sliding of the knife over the surface of the metal plate. The creasing-blade continuing to descend the metal plate is drawn between the rollers 51 52 and doubled, as will be apparent. A complete downward movement of the creasing-blade is effected by a half-revolution of the pulley 9. As the pulley 9 continues to revolve the creasing-blade will begin to rise; but the tilting platform 45 will remain stationary for a slight interval of time owing to the fact that the crank-pin 15 will slide in the slot 17 of the connecting-rod 16. This movement of the creasing-blade in advance of the tilting platform is to 65 facilitate the dropping of the doubled plate upon said platform. In the continued movement of the parts the creasing-blade is raised, 70 the block 76 contacts with the outer end of trip-lever 76 to restore the gage-plates 59 to their outer positions, and the free end of the tilting platform 45 is raised, whereby the doubled sheet will slide from said platform 75 onto the receiving-table 82, as shown in Fig. 1.

In order to center the spring-pressed rollers 51 52 in relation to the creasing-blade, I 80 may locate the upright 41 to extend between one set of bearing-blocks 53, and the section 85 or continuation of the upright 40, secured in the side member 3, may also extend at its upper end between the opposite pair of blocks 53, whereby the rollers 51 52 cannot be pressed inward beyond a certain point. 90

By affording a slotted connection of the 95 various connecting-rods and levers with the parts to which they are connected I provide for adjustment to vary the throw of said connecting-rods and levers, as will be clearly 100 understood.

Having thus fully described my invention, what I claim as new, and desire to secure by Letters Patent of the United States, is—

1. In a doubling-machine, a pair of creasing-rolls adapted to support the metal plate to be doubled and a vertically-reciprocating creasing-blade co-operating therewith and designed to force the metal plate between said rolls whereby said plate is doubled, substantially as described. 120

2. In a doubling-machine, a pair of spring-pressed creasing-rolls, and a vertically-reciprocating creasing-blade designed to pass between said rolls, substantially as described. 125

3. In a doubling-machine, a pair of creasing-rolls, a vertically-reciprocating creasing-blade co-operating therewith, and a swinging platform arranged beneath said rollers and 130

actuated to receive and deliver the doubled plate, substantially as described.

4. In a doubling-machine, a table designed to support the metal plates to be doubled, creasing-rolls journaled in said table, a vertically-reciprocating creasing-blade coöperating with said rolls, gage-plates slidably supported on either end of said table and means for drawing the gage-plates toward each other coincidently with the downward motion of the creasing-blade, substantially as described.

5. In a doubling-machine, a pair of creasing-rolls, a vertically-reciprocating creasing-blade coöperating therewith, a tilting platform arranged beneath said rollers and designed to receive and deliver the doubled plates, and means for raising and lowering the free end of said platform in unison with the rise and fall of the creasing-blade, substantially as described.

6. In a doubling-machine, a table designed to support the metal plates to be doubled, creasing-rolls journaled in said table, a vertically-reciprocating creasing-blade coöperating with said rolls, a tilting platform arranged beneath said rollers, means for turning said platform to a lower inclined position coincidently with the fall of the creasing-blade to receive the doubled plate from said blade, means for turning said platform to an upper inclined position whereby to permit the doubled plate to slide from the rear end of said platform, and an inclined receiving-table located in the table in operative relation with said tilting platform, substantially as described.

7. In a doubling-machine, a pair of creasing-rolls, a vertically-reciprocating creasing-blade coöperating therewith, a tilting platform arranged beneath said rollers and designed to receive and deliver the doubled plates, means for raising and lowering the free end of said platform in unison with the rise and fall of the creasing-blade, and means for imparting an upward movement to the creasing-blade in advance of the upward movement of the tilting platform, substantially as described.

8. In a doubling-machine, a table designed to support the plate to be doubled and having grooves in its upper surface, spring-pressed slide-blocks located in said grooves, creasing-rolls journaled at their ends in said blocks, stops to limit the inward movement of said blocks, and a vertically-reciprocating creasing-blade coöperating with said creasing-rollers, substantially as described.

9. In a doubling-machine, a table designed to support the metal plates to be doubled, creasing-rolls journaled in said table, a vertically-reciprocating creasing-blade coöperating with said rolls, gage-plates slidably supported on either end of said table, guides on said gage-plates terminating in friction-rollers, and means for drawing the gage-plates toward each other coincidently with the down-

ward motion of the creasing-blade, substantially as described.

10. In a doubling-machine, a table designed to support the metal plates to be doubled, a vertically-reciprocating creasing-blade, uprights affording guideways for said creasing-blade, the outer upright being cut away to permit of the plates being placed on the table, downwardly-curved guide-fingers secured on the front of said table and an upwardly-curved guide-finger slidably supported on the lower end of said cut-away upright, substantially as described.

11. In a doubling-machine, a pair of creasing-rolls, a vertically-reciprocating creasing-blade coöperating therewith, a swinging platform arranged beneath said rollers and actuated to receive and deliver the doubled plate, and a catch-plate carried by the outer free end of said platform, substantially as described.

12. In a doubling-machine, a table designed to support the metal plates to be doubled, a shaft journaled in said table carrying a tilting platform, and having secured thereon a pinion, a rack-bar for operating said pinion, a drive-pulley having a crank-pin, a vertically-movable creasing-blade, means operatively connecting said creasing-blade and drive-pulley, and a connecting-rod pivotally connected at one end to said rack-bar and at its opposite end having a slotted connection with the crank-pin on the drive-pulley, substantially as described.

13. In a doubling-machine, a table designed to support the metal plates to be doubled, a shaft journaled in said table carrying a tilting platform and having secured thereon a pinion, a rack-bar for operating said pinion, a drive-pulley having an adjustable crank-pin, a vertically-movable creasing-blade, means operatively connecting said creasing-blade and drive-pulley, and a connecting-rod pivotally connected at one end to said rack-bar and at its opposite end having a slotted connection with the crank-pin on the drive-pulley, substantially as described.

14. In a doubling-machine, a table designed to support the metal plates to be doubled, gage-plates slidably supported on said table, a shaft journaled in said table carrying crank-plates, a pair of connecting-rods at either side of the table having, respectively, their outer ends connected to said gage-plates and their inner ends connected to opposite sides of said crank-plates, coiled springs each of which is connected at one end to the table and at its other end to one connecting-rod of each pair, and means for turning said shaft against the resistance of said springs, substantially as described.

15. In a doubling-machine, a table designed to support the metal plates to be doubled, gage-plates slidably supported on said table, a shaft journaled in said table carrying crank-plates and having a crank-arm, a pair of con-

necting-rods at either side of the table having respectively, their outer ends connected to said gage-plates and their inner ends connected to opposite sides of said crank-plates, 5 coiled springs, each of which is connected at one end to the table and at its other end to one connecting-rod of each pair, a trip-lever having an outer free end and an inner end pivotally connected by a link with the crank- 10 arm of said shaft, a vertically-movable creasing-blade, a lever-arm connected at one end

to said creasing-blade and having an outer free end adapted to contact with the outer end of said trip-lever, and means for operating said lever-arm, substantially as described. 15

In testimony whereof I have hereunto set my hand in presence of two subscribing witnesses.

FELIX WESTWOOD.
